SPOON

Robert V. Locander, Milwaukee, Wis.

Application April 8, 1954, Serial No. 29,913

Term of patent 14 years

(Cl. D44—29)

To all whom it may concern:

Be it known that I, Robert V. Locander, a citizen of the United States of America and resident of the city of Milwaukee, county of Milwaukee, State of Wisconsin, have invented a new, original, and ornamental Design for a Spoon, of which the following is a specification, reference being had to the accompanying drawing, forming a part hereof.

Fig. 1 is a top plan view of a spoon showing my new design;

Fig. 2 is a front elevational view thereof;

Fig. 3 is a bottom plan view thereof; and

Fig. 4 is a view in side elevational view thereof.

I claim:

The ornamental design for a spoon, as shown.
